CLAIM

The ornamental design for a belt, as shown and described.

DESCRIPTION

FIG. 1 is a top, front, right perspective view of a belt showing our new design, with the belt shown in a first configuration;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear view thereof, with the belt shown in a second configuration.

The even-length broken lines represent stitching. The uneven-length broken lines immediately adjacent to the shaded area define the bounds of the claimed design and form no part thereof. The uneven-length broken lines depicting the remainder of the belt show portions that form no part of the claimed design.
